HELICAL CROSS TIE

Hugh Leal, Windsor, Ontario, Canada, assignor
to L. A. Young Spring & Wire Corporation,
Detroit, Mich.

Application April 13, 1933. Serial No. 665,909

2 Claims. (Cl. 5—269)

The main object of this invention is to provide a helical connector or tie member for spring cushion structures having terminal hooks which enable the quick and secure engagement of the 5 connector with body springs of a cushion structure or the like.

A further object is to provide a helical tie member or connector in which the terminal hooks are so positioned that pull on the spring is central or in the longitudinal central plane thereof.

Objects pertaining to details and economies of my invention will definitely appear from the description to follow. The invention is defined in the claims.

15 A structure embodying the features of my invention is clearly illustrated in the accompanying drawing, in which:

Fig. 1 is a fragmentary plan view of a spring cushion structure illustrating an application of 20 my improved spring tie or connector unit.

Fig. 2 is a fragmentary view further illustrating the form of the hook, the engaged part being shown by dotted lines.

Fig. 3 is an end view of the engaged part shown 25 in dotted line.

Fig. 4 is a fragmentary perspective view illustrating the manner of engaging the hook.

In the accompanying drawing, 1 represents the body springs of a spring cushion or bed structure 30 and 2 the border frame thereof. My improved helical connector or tie members 3 are formed of suitable gage wire and terminate in hooks 4 by which the connectors or tie members are secured to the end coils of the body springs. In forming 35 these hooks the springs are cut into suitable length and complete end coils and segmental portions of adjacent coils are disposed at an angle to the normal pitch of the coils, providing the circular hooks 4 with inwardly offset shank portions

40 5. The bills 6 of the hooks lie in spaced overlapping relation to the inwardly offset shank portions 5, thereby facilitating the engagement of the hooks with the parts to be connected, such as the end coils of the body springs. The bills of 45 the hooks lie within the diameter of and close to the adjacent end coils 7 which constitute guards for the hooks.

By reference to Figs. 2, 3 and 4 it will be observed that the hooks and the adjacent end coils 50 form a flaring mouth or guide to facilitate engagement of the hooks with the parts, it only being necessary to present this flaring mouth to the part to be engaged and push on the spring which forces the part to be engaged between the 55 offset shank and the bill of the hook, the part snapping under the bill of the hook and adjacent to the end coil 7 which constitutes a guard for the hook. It is very difficult, in fact, quite impossible, to disengage the hooks without such 60 stress as would deform the hook or require care-

ful manipulation by a tool or otherwise to spring the bill of the hook over the engaged part.

It will be observed that the inward offsetting of the coil forming the hook, as best shown in Fig. 2, provides a shoulder or hump at the end of the undeformed portion of the adjacent coil, and that this shoulder or hump is in opposed relation to the bill of the hook. This greatly facilitates the application of the tie member and also renders it very difficult to disengage without manual manipulation or severe stress such as would distort the parts, and they are, of course, designed to withstand the stress to which they are normally subjected. Engagement is effected by a very slight rotary movement, that is, the element 65 is presented to the coil of the body spring so that it enters the throat between the bill and the opposed hump, and a slight twisting or rotary movement is effective to engage the hook. To disengage the parts they must be manually manipulated by means of a tool to get the spring 70 under the bill as removing stress tends to swing the bill toward the hump, or the structure must be subjected to such twisting stress as will spring the hook. Such stress is unlikely in normal 75 operation.

The bights of the hooks lie in approximately the longitudinal center plane of the helical connectors so that there is a minimum tendency to distort the connectors under stress. The connectors may be very easily and quickly engaged 80 and are very secure. In practice they are preferably arranged in crossed inter-engaging pairs as shown in the drawing. While the connector is especially designed and adapted for use in spring cushion structures, it is desirable for use in other 85 relations, particularly where rapid and easy attachment of the spring is desired.

Having thus described my invention what I 90 claim as new and desire to secure by Letters Patent is:

1. A helical connector having complete end coils thereof and segments of the adjacent coils disposed at an angle to the normal pitch of the coils providing circular hooks with inwardly offset shank portions, the bills of the hooks lying in spaced overlapping relation to the inwardly offset shank portions of the hooks and lying within the diameter of and close to the adjacent coils which coils constitute guards therefor.

2. A helical connector for spring structures having the end coils thereof disposed at an angle to the normal pitch of the coils providing circular hooks, there being inward offsets at the bases of the hooks, the bills of the hooks lying in overlapping relation to such offsets and terminating within the diameter of and close to the adjacent coils which constitute guards therefor.
